UNITED STATES PATENT OFFICE.

CLARENCE H. FREDERICK, OF KENOSHA, WISCONSIN, ASSIGNOR TO THE SIMMONS MANUFACTURING COMPANY, OF KENOSHA, WISCONSIN, A CORPORATION OF WISCONSIN.

FABRIC-MAKING MACHINE.

1,176,138.

Specification of Letters Patent. Patented Mar. 21, 1916.

Application filed March 18, 1914. Serial No. 825,469.

To all whom it may concern:

Be it known that I, CLARENCE H. FREDERICK, citizen of the United States, residing at Kenosha, in the county of Kenosha and 5 State of Wisconsin, have invented a certain new and useful Improvement in Fabric-Making Machines, of which the following is a full, clear, concise, and exact description, reference being had to the accompanying 10 drawings, forming a part of this specification.

My invention relates to machines for making fabrics and, in its preferred embodiment, includes characteristics of construction, 15 which are covered by claims contained in my United States Patent No. 1,148,766, granted August 3, 1915.

By means of my invention fabric units which are being assembled into a fabric are 20 individually joined to a previously formed fabric portion. My machine is of particular service in the formation of those fabrics wherein the units are formed into rows by their attachment to previously formed rows, 25 though obviously the invention is not to be limited to the formation of such a fabric.

I will explain my invention more fully by reference to the accompanying drawings showing the preferred embodiment thereof 30 and in which—

Figure 1 is a front view of a machine constructed in accordance with the invention, a part of the machine being broken away owing to lack of space; Fig. 2 is a view in 35 front elevation illustrating the proportion which the length of the complete machine bears to its height; Fig. 3 is a plan view of the structure illustrated in Fig. 1; Fig. 4 is a sectional view on line 4—4 of Fig. 3; Fig. 40 5 is a sectional view on line 5—5 of Fig. 4; Fig. 6 is a view on line 6—6 of Fig. 7; Fig. 7 is a view on line 7—7 of Fig. 6; Fig. 8 is a view of a part of the mechanism taken in the direction of arrow 8 in Fig. 1; Fig. 9 is a side elevation of the structure illustrated 45 in Fig. 8; Fig. 10 is a view of a part of the mechanism taken in the direction of arrow 10 of Fig. 1; Fig. 11 is a sectional view on line 11—11 of Fig. 1; Fig. 12 is a view generally taken on line 12—12 of Fig. 10, the parts being slightly readjusted in Fig. 12 to reveal a characteristic of construction; Fig. 13 is a view on line 13—13 of Fig. 1; Fig. 14 is a view illustrating a part of a 50 fabric which may be constructed by means

of my machine; and Fig. 15 is a perspective view of one of the units entering into the fabric a part of which is shown in Fig. 14.

Like parts are indicated by similar characters of reference throughout the different 60 figures.

Power is applied to the machine in any suitable way, for example, with the aid of a driving pulley 1 in permanently fixed relation to a driving shaft 2. This shaft operates mechanism for forming the fabric units 3, this mechanism not being specifically claimed herein but being included as an integral part of the machine for the sake of convenience and economy and as affording a suitable source of supply for the fabric units which are to be included in a fabric by means of the mechanism of my invention. I will therefore give only a short description of the fabric unit making mechanism. This mechanism includes cams 4, cam rollers 5 riding upon the cams 4, cam levers 6 carrying the cam rollers 5, adjustable pushers 7 carried by the levers 6, and fabric unit forming slides 8 pressed inwardly by 70 the pushers 7 when said pushers are pushed inwardly and withdrawn by springs 9 when the pushers 7 are withdrawn. There is also included a stationary pin 10 (which I also employ as a part of the mechanism of my invention) and a forming block 11, which elements 10 and 11 coöperate with forming dies 12 that act upon pieces of wire of predetermined length to form the fabric units 75 3 (Fig. 5).

The wire which is fed to the machine is illustrated at 13 and is cut into pieces of different lengths for the purpose of enabling the formation of the fabric units 3 by means of a cutter 14 operated by a cam 15 turning 95 with the main shaft 2. The hook ends 3¹ are formed of benders *a* which are in gear connection with rack-bars *b*, these rack-bars being spring-pressed by springs *c* to restore the benders to their normal positions and being forwardly moved to operate the benders by adjustable pushers *d* carried by levers *e* which in turn carry cam rollers *f* that ride upon cams *g* for the purpose of controlling the actuation of the rack-bars *b*. Strippers 100 *h* operate to strip the wire from the benders, these strippers being operated by a lever *i* carrying a cam roller *k* operated upon by a cam *l*. During the operation of the benders the wire is pressed against the pin 10 by a 105 110

clamping member *m* which is operated upon by a lever *o* carrying a roller *p* operated upon by a cam *q*. The formed fabric units are pushed from the forming block 11 on to a reel 16 constituting the preferred form of temporary fabric link unit support, driven as hereinafter described, each fabric unit being received between adjacent pins 17 and beneath the heads of these pins.

10 The mechanism which I employ for pushing the formed fabric units from the block 11 includes a pair of pushing pins 18 which are pressed rearwardly by coil springs 19 for the purpose of withdrawing the pins after they have operated, and which pins are caused to perform their function by being pushed forwardly by adjustable pushers 20 carried upon levers 21. These levers 21 carry cam rollers 22 which turn upon cams 23. The pins 18 engage upper portions of a formed fabric unit 3 and an additional pusher 24 is provided for engaging a lower portion of the formed fabric unit, this pusher being spring pressed rearwardly by a coil spring 25 for the purpose of withdrawing the pusher 24 after its has operated, and which pusher is caused to perform its function by being pushed forwardly by a pusher 26 carried upon a lever 27. This lever 27 carries a cam roller 28 which turns upon a cam 29. The pushing devices 18 and 14 coöperate to push the fabric unit from the block 11 so that this fabric unit will temporarily occupy the position illustrated in dotted lines in Fig. 13. The pusher 24 is now operated, while the pushers 18 are stationary, to push the lower end of the formed fabric unit from the forming pin 10. At this time a cam nose 30 upon the reel 16 is positioned with its point between the sides of the formed fabric unit, the nose 30 being sufficiently broad at its base to have such cam action upon the fabric unit as to cause this fabric unit to be lowered as the fabric unit is being brought to a vertical position, the lowering of the fabric unit not occurring, however, until it has been stripped from the forming pin 10. When the pusher 24 has pushed the fabric unit against the reel 16 the fabric unit has been lowered from the position illustrated by dotted lines in Fig. 13 to a position in which the hooks 31 are engaged each with a loop 32 of adjacent fabric units disposed upon the top of the reel by a previous operation. During the forward and downward movement of the fabric unit that is being displaced from the forming block the sides of the fabric unit under removal slip over the heads of adjacent pins 17 so that the fabric unit in its final position is lowered and is also held in position by adjacent pins 17. The free ends of the hooks 31, having now been passed through the loops 32, are in readiness to be pressed toward their complemental sides, an operation

which occurs after the anvils 31 have been lowered to the position to engage the hook ends 31 after which the forward movement of the pusher pins 18 is continued sufficiently to mash the hook ends 31 against their complemental sides whereby the newly formed fabric unit is articulated with the loops 32 of two previously formed fabric units. The anvils 31 are mounted upon a common lever 32 which is provided with tapering grooves 33 in which a pin 34 may have limited play with respect to the lever 32. A forward movement of a shaft 35 carrying the pin 34 will permit the anvils 31 to lower, the shaft 35 being in fixed relation with a lever 36 which carries a cam roller 37 adapted to turn upon a cam 38. The object of providing the tapering grooves 33 is to enable the anvils 31 to remain suspended during all of these forward movements of the rod 35 which occur during the formation of the first row of a new fabric whereby separated fabrics of definite or predetermined length may be discharged by the machine, since the hooks at 31 of the first row of a new fabric 90 are not closed owing to the then elevated positions of the anvils 31. By means of mechanism to be hereinafter described the anvils 31 are maintained in their elevated positions for the purpose stated by means of a hook 95 39 which is maintained in engagement with a pin 40 carried by the lever 32 during the formation of the first row of the new fabric. After each freshly formed fabric unit has been applied to the left-hand vertical face 100 of the reel 16 (Fig. 4) said reel is moved longitudinally of itself a fabric unit space. When these fabric units are in the first row of a new fabric the anvils 31 are maintained elevated, as described, but in the succeeding rows of the same fabric the anvils 31 are brought into play for the purpose specified, each fabric unit of the succeeding rows, as it is added to its row, being applied to adjacent fabric units of the precedingly 110 formed row whereby the formation partially illustrated in Fig. 14 results. The reel is reciprocated the whole extent in one direction during the formation of one row and is preferably reciprocated in the return direction during which return reciprocation the next row is formed, though I do not wish to be limited to the formation of fabric unit rows during each reciprocal movement of the reel. It is understood 115 that the reel is turned after it has been moved longitudinally of itself sufficiently to enable the formation of a row of fabric units before the next row of fabric units is formed. The mechanism by which the reel is reciprocated is illustrated most clearly in Figs. 1, 4, 6 and 7. The ends of the reel 16 are journaled in bearings 41 and these bearings are provided with arms 42 through which a guide rod 43 passes. 120

The near walls of the reel are provided with square openings that are in sliding fit with the spur shaft 44, the shafts 43 and 44 thus coöperating to maintain the reel in the position to which it is turned, the shaft 44 being turned 90° after the formation of each row of fabric units, in a manner to be described. The outer ends of the arms 42 are united by a T-member 45 which constitutes a mounting for rack bars 46, 47 which are fixed upon the mounting 45 and are therefore fixed with respect to each other. These rack bars respectively have teeth 48 (shown in dotted lines in Fig. 6) and teeth 49 (shown in full lines in Fig. 6), the teeth upon one rack bar sloping oppositely to the teeth of the other. An actuating pawl 50 coöperates with the teeth 48 to reciprocate the rack bar 46 step by step while the actuating pawl 51 coöperates with the teeth 49 to move the rack bar 47 step by step, means being provided for holding one pawl out of action while the other pawl is in action so that an operating pawl 25 will cause step-by-step movement of its rack-bar together with the T-member 45, the arms 42, the bearings 41, and the reel 16. Pawl 50 is carried by the bar 52 and pawl 51 is carried upon the bar 53. An adjustable pusher 54 operates to push the bar 52 in turn to push the pawl 50 when this pawl is to move its rack-bar 46, the pusher 54 being withdrawn each time it has caused a movement of the rack-bar 46, 30 the spring 55 then operating to withdraw the pawl carrier 52 in readiness to enable the pusher 54 again to push the carrier 52, each actuating movement of the pusher 54 and the consequent results occurring 35 after a fabric unit has been freshly applied to the reel 16. The pusher 54 is mounted upon a lever 56 which carries a cam roller 57 that is operated upon by a cam 58. An adjustable pusher 59 operates to push the bar 53 in turn to push the pawl 51 when this pawl is to move its rack-bar 47, the pusher 59 being withdrawn each time so as to cause a movement of the rack-bar 47, the spring 60 operating to withdraw the 40 pawl carrier 53 in readiness to enable the pusher 59 again to push the carrier 53, each actuating movement of the pusher 59 and the consequent results occurring after a fabric unit has been freshly applied to the reel 45 16. The pusher 59 is mounted upon a lever 61 which carries a cam roller 62 that is operated upon by a cam 63. It is understood that the cams *g*, *l*, *g*, 4, 23, 29, 38, 58, and 63 are in fixed relation to the main shaft 2, whereby the various cam operations occur in orderly sequence.

The left-hand arm 42 is interposed between and is coöperatively related with two collars 64, 65, said left-hand arm 42 being in engagement with the collar 64 during the

longitudinal movement of the reel 16 through a space equal to one and one-half times the regular tooth spaces or one and one-half times a fabric unit space when the reel is finishing its movement to the left. 70 When the reel is finishing its movement to the right the left-hand arm 42 engages the collar 65 to move it a similar space, to return the collar 64 to its first position. Thus the rod 43, to which the collars 64 and 65 are 75 fixed, is moved to the left a space and a half, as the right-hand end of one row is finished and a space and a half to the right as the left-hand end of the companion row is finished. The rod 43 carries a collar 66 80 with sloping ends, this collar being shown in Fig. 1 in engagement with a roller 67. The movement of the rod 43 one tooth or fabric unit space to the left from the position illustrated in Fig. 1 is just sufficient 85 to transfer the collar 66 from one side of the roller 67 to engagement with the other side of this roller, the additional movement of the rod 43 through a half a space moving the collar 66 a half space to the left 90 from the roller 67, this result occurring when the reel has been moved to its leftmost position. When the reel has been moved to its rightmost position the arm 42 will engage the collar 65 to restore the collar 66 to 95 the position illustrated in Fig. 1. Each time the collar 66 passes beneath the roller 67 it raises said roller and the right-hand end of a similarly pivoted lever 68 against the force of a spring 69. The left-hand end 100 of the lever 68 is thereupon depressed to remove the wedging cam 70 carried thereby (Figs. 3, 11 and 12) from engagement with the closure pin or member 71 whereupon the expansion spring 72 is free to 105 move the pin 71 toward a collar 73 which is fixed on the shaft 2. When the shaft 2 turns the collar sufficiently to present the opening 74 therein to the pin 71 the spring 72 will insert the pin 71 in the opening 74 110 whereby said pin couples the collar 73 with the collar 75 that carries the pin 71 so that the collars 73 and 75 will then turn together, the collar 73 being unaccompanied by the collar 75 when the pin 71 is out of 115 engagement with the collar 73. The cam 76 is thus turned one complete revolution by the shaft 2 at the conclusion of the formation of each row of fabric units, the slot 77 in the pin 71 being in position, when the pin 71 is within the opening 74, to receive the sharp end or toe of the shoe 70 when the cam 76 nears the completion of its revolution so that at the conclusion of the revolution of this cam the pin 71 is fully withdrawn from the recess 74 whereby the cam 76 is limited to its single revolution at the conclusion of the formation of each row of fabric units.

A ratchet wheel 78 is in fixed relation to 120

the reel and has four equidistant peripherally elongated teeth each adapted to be engaged by an actuating pawl 79 mounted upon an arm 80 loosely mounted upon a cylindrical continuation of the shaft 44. A link 81 is pivotally connected at one end to the face of the cam 76 and at the other end is connected with the arm 80 so that as the cam 76 turns one revolution it causes the link 81 to operate the pawl 79 to turn the shaft 44 and reel 16 carried thereby a quarter turn, the pawl 79 being withdrawn to its starting point when the revolution of the cam 76 has ceased. In this way the reel 16 is turned a quarter turn each time a row of fabric units is formed. A holding wheel 82 is also in fixed relation with the reel and has four notches 83 adapted to receive a holding pawl 84 which is shown in Fig. 10 as being received in one of the recesses 83. After the reel has been turned a quarter turn the periphery of the cam 76 operates upon a roller 85 that is carried by a cam lever 86 to turn said cam lever to bring the holding pawl 84 into engagement with the lowermost notch 83 whereby the reel 16 is firmly held from rotation (though it is free to move longitudinally of itself) during the ensuing formation of a new row of fabric units.

As the machine is organized the pushers 54, 59 mutually approach when they push upon their associate pawl bars 52, 53 and mutually separate when the springs 55, 60 operate to restore these bars. On this account means are provided for throwing one or the other of the pawls 50, 51 out of action. This means includes a plate 87 the middle and shorter portion of which underlies the racks 46 and 47. When the plate 87 is adjusted to the right it will overlie the pawl 51 to prevent this pawl from operating and when adjusted to the left it will overlie the pawl 50 to prevent this pawl from operating whereby the reel 16 may be limited to co-operative relation with and the actuating influence of one or the other of the pawls 50, 51. The plate 78 is shifted out of engagement with one of the pawls 50, 51 into engagement with the other as each row of fabric units is completed. The rack bar 47 is chamfered at its left hand end as indicated in full lines in Fig. 6 while the rack bar 46 is chamfered at its right hand end as indicated by the sloping dotted line at the right of Fig. 6. The pawl carrying bar 52 also carries a composite pawl made up of an upwardly spring pressed portion 88 and gravity operated portion 89, the portion 88 carrying a pin 90 underlying the portion 89 and being sloped at its upper end and there engaging a rack bar 47 so as to have its position determined and whereby the portion 88 is adapted to rise when moving over the chamfered left hand end of the bar 47 then

to cause the pin 90 to raise the pawl section 89 into the plane of the plate 87 whereby the plate is moved to the right to uncover and render operative the pawl 50 as the rack bar 47 finishes its stroke to the left whereby the pawl 50 is brought into co-operative relation with the rack bar 46 and the plate 87 covers the pawl 51 to remove it from operative relation with the rack bar 47. The pawl carrying bar 53 also carries a composite pawl made up of an upwardly spring pressed portion 91 and gravity operated portion 92, the portion 91 carrying a pin 93 underlying the portion 92 and being sloped at its upper end and there engaging a rack bar 46 so as to have its position determined and whereby the portion 91 is adapted to rise when moving over the chamfered right hand end of the bar 46 then to cause the pin 93 to raise the pawl section 92 into the plane of the plate 87 whereby the plate is moved to the left to uncover and render operative the pawl 51 as the rack bar 46 finishes its stroke to the right whereby the pawl 51 is brought into co-operative relation with the rack bar 47 and the plate 87 covers the pawl 50 to remove it from operative relation with the bar 46. When the plate 87 is thus shifted to the left the pawl 51 comes into contact with rack-bar 47 midway between two teeth whereby the first step movement of the bar 47 is through a distance equal to a half tooth space after which the movements of the bars 47 are each equal to a full tooth space until the last movement is reached whereupon the movement of the bar 47 is again only a half tooth space, a result which is accomplished by spacing the last tooth at the left of the bar 47 a half tooth space toward its lever at its right. By observing Fig. 14 the reason for the half movements of the bar 47 at the beginning and end of its movement to the right will be understood when it is stated that the step by step movements of this bar 47 to the right accompany the formation of each shorter row of fabric units which must have, in the fabric shown, one less unit than each longer row. Each time the reel 16 is turned a quarter turn one of the four pins 94 engages a pawl carrier 95 to move this carrier a sufficient extent to cause the pawl 96 carried thereby to move the ratchet wheel 97 one tooth space. The wheel 97 is shown as being provided with twenty teeth, the machine being adapted to the formation of a fabric having twenty rows of fabric units. When the last row of a fabric has been formed the ratchet wheel 97 springs the notch 98 in the wheel 99 into register with the nose 100 of the spring pressed rider 101 whereby the rider moves inwardly toward the wheel 97, it being understood that the wheels 97 and 99 are in fixed relation. The rider 101 is fixed

upon the shaft 102 upon which the hook 39 is also fixed (Fig. 4) whereby the hook 39 is placed beneath the pin 40 carried by the anvil structure 31 when the rider 101 moves toward the wheel 97 to prevent the first row of the new fabric from being attached to the last row of the completed fabric. In reading Figs. 4 and 8 in connection with each other it should be remembered that these views are taken in opposite directions. The wheels 97 and 99 are mounted upon a common shaft 103, a spring 104 operating to prevent these wheels from being shifted beyond the positions in which they are brought by the pawl 96 until said pawl again operates.

While the mechanism for forming the links or fabric units is not broadly new with me, yet the relationship of the fabric unit forming mechanism and the fabric unit assembling mechanism is considered broadly novel.

While I have herein shown and particularly described the preferred embodiment of my invention I do not wish to be limited to the precise details of construction shown as changes may readily be made without departing from the spirit of my invention.

Having thus described my invention I claim as new and desire to secure by Letters Patent the following:

1. A machine for forming fabric which includes mechanism for forming wire into fabric units; mechanism for joining the fabric units singly and side by side to a previously formed fabric portion; and means for transferring the formed fabric units from the former to the latter mechanism.

2. A machine for forming fabric including means for forming wire into fabric units; mechanism for distributing the fabric units in rows and attaching fabric units as they are distributed in their rows to previously formed rows of fabric units; and means for transferring the formed fabric units from the former to the latter mechanism.

3. A machine for forming fabric which includes a reel; means for transferring fabric units to the reel; fabric units joining mechanism for joining adjacent units while upon the reel; and means for effecting relative step by step movement between the reel and the fabric unit joining mechanism and also between the reel and said transferring means whereby fabric units are distributed in rows upon the reel and fabric units are connected with adjacent fabric units in an adjacent row.

4. A machine for forming fabric which includes a reel; means for transferring fabric units to the reel; fabric unit joining mechanism for joining said units one at a time with adjacent units supported by said

reel; and means for effecting relative step by step movement between the reel and the fabric unit joining mechanism and also between the reel and said transferring means whereby fabric units are distributed in rows upon the reel and fabric units are connected with adjacent fabric units in an adjacent row.

5. A machine for forming fabric which includes a reel; fabric unit joining mechanism for joining adjacent units while upon the reel; and means for effecting relative step by step movement between the reel and the fabric unit joining mechanism whereby fabric units are connected with adjacent fabric units in an adjacent row.

6. A machine for forming fabric which includes a fabric unit support; means for transferring fabric units to the fabric unit support; fabric unit joining mechanism for joining adjacent units while upon the fabric unit support; and means for effecting relative step by step movement between the fabric unit support and the fabric unit joining mechanism and also between the fabric unit support and said transferring means whereby fabric units are distributed in rows upon the fabric unit support and fabric units are connected with adjacent fabric units in an adjacent row.

7. A machine for forming fabric which includes a fabric unit support; means for transferring fabric units to the fabric unit support; fabric unit joining mechanism for joining units one at a time with adjacent units supported by the fabric unit support; and means for effecting relative step by step movement between the fabric unit support and the fabric unit joining mechanism and also between the fabric unit support and said transferring means whereby fabric units are distributed in rows upon the fabric unit support and fabric units are connected with adjacent fabric units in an adjacent row.

8. A machine for forming fabric which includes a fabric unit support; fabric unit joining mechanism for joining adjacent units while upon the fabric unit support; and means for effecting relative step by step movement between the fabric unit support and the fabric unit joining mechanism whereby fabric units are connected with adjacent fabric units in an adjacent row.

9. A machine for forming fabric which includes a reel; means for transferring fabric units to the reel; fabric unit joining mechanism for joining adjacent units while upon the reel; means for effecting relative step by step movement between the reel and the fabric unit joining mechanism and also between the reel and said transferring means whereby fabric units are distributed in rows upon the reel and fabric units are connected with adjacent fabric units in an adjacent row.

units in an adjacent row; and means for effecting the omission of the connection of units of the last row of one formed fabric with units of the first row of the next fabric to be formed.

- 5 10. A machine for forming fabric which includes a reel; means for transferring fabric units to the reel; fabric unit joining mechanism for joining units one at a time with adjacent units supported on said reel; means for effecting relative step by step movement between the reel and the fabric unit joining mechanism and also between the reel and said transferring means whereby fabric units are distributed in rows upon the reel and fabric units are connected with adjacent fabric units in an adjacent row; and means for effecting the omission of the connection of units of the last row of one 15 formed fabric with units of the first row of the next fabric to be formed.

15. A machine for forming fabric which includes a fabric unit support; fabric unit joining mechanism for joining adjacent units while upon the fabric unit support; means for effecting relative step by step movement between the fabric unit support and the fabric unit joining mechanism whereby fabric units are connected with adjacent fabric units in an adjacent row; and means for effecting the omission of the connection of units of the last row of one formed fabric with units of the first row of the next fabric to be formed.

16. A machine for forming fabric which includes a fabric unit support; fabric unit joining mechanism for joining units one at a time with adjacent units on said support; means for effecting relative step by step movement between the fabric unit support and the fabric unit joining mechanism whereby fabric units are connected with adjacent fabric units in an adjacent row; and means for effecting the omission of the connection of units of the last row of one formed fabric with units of the first row of the next fabric to be formed.

17. In a machine for making wire fabric composed of transverse, interconnected, adjacent rows of identical adjacent and connected metal fabric units, each of said units having an eye portion at one side of the transverse row and a mating hook portion at the other side of said row, said mating portions connecting together the adjacent rows of the fabric, the combination of a support for carrying the finished length of fabric, mechanism for cutting unit lengths from the end of a continuous wire supply, partly forming said unit lengths and engaging the same with the end of the finished fabric carried by said support, and means for effecting relative step-by-step, movements of the fabric-support and said severing, forming and engaging mechanism.

18. In a machine for making wire fabric composed of transverse, interconnected, adjacent rows of identical adjacent and connected metal fabric units, each of said units having an eye portion at one side of the

transverse row and a mating hook portion at the other side of said row, said mating portions connecting together the adjacent rows of fabric, the combination of a support for carrying the finished length of fabric, mechanism for cutting unit lengths from the end of a continuous wire supply, partly forming said unit lengths and engaging the same with the end of the finished fabric carried by said support, means for completing each of said unit lengths, one at a time, after its engagement with said fabric, and means for effecting relative step-by-step movements of the fabric-support and said severing, forming and engaging mechanism.

19. In a machine for making wire fabric composed of transverse, interconnected, adjacent rows of identical, adjacent and connected metal fabric units, each of said units having an eye portion at one side of the transverse row and a mating hook portion at the other side of said row, said mating portions connecting together the adjacent rows of the fabric, the combination of a support for carrying the finished length of fabric, mechanism for cutting unit lengths from the end of a continuous wire supply, partly forming said unit lengths and engaging the same with the end of the finished fabric carried by said support, means for completing each of said unit lengths, one at a time, after its engagement with said fabric, means for effecting relative step-by-step movements of the fabric-support and said severing, forming and engaging mechanism, and means for effecting automatic reversals of said step-by-step movements after a predetermined number of steps, whereby a flat fabric of predetermined width is produced.

20. In a machine for forming a continuous length of wire fabric composed of transverse, adjacent, interconnected rows of identical, adjacent connected wire fabric units, each of said units having an eye at one side of the transverse row in which it is located, and a mating hook at the opposite side of said row, said adjacent parts constituting the inter-engaging longitudinal connections between the adjacent rows, the combination of mechanism for initially forming said fabric units, one at a time, a support for carrying a finished length of fabric, means for connecting the partly formed fabric units, one at a time, to the end of the finished fabric carried by said support, means for completing the unit after its engagement with said fabric, and means for effecting relative movements of the fabric-support and said forming mechanism.

21. In a machine for forming a continuous length of wire fabric composed of transverse, interconnected, adjacent rows of

identical, adjacent, connected wire fabric units, each of said units having an eye part and a hook part mating with the eye part of a unit in an adjacent row, said mating parts connecting together adjacent units of the fabric, the combination of mechanism for cutting off unit lengths, one at a time from a continuous wire supply, partly forming said unit lengths and engaging the same with the end of a previously completed fabric length, a support for carrying the finished fabric length, means for completing the unit after its engagement with the fabric on said support, and means for effecting relative step-by-step movements of the fabric-support and said severing, forming and engaging mechanism, whereby a continuous length of fabric is produced.

22. In a machine for forming a continuous length of wire fabric composed of transverse, interconnected, adjacent rows of identical, adjacent connected wire fabric units, each of said units having an eye part and a hook part mating with the eye part of a unit in an adjacent row, said eye and hook parts connecting together adjacent fabric units in said fabric, the combination of mechanism for severing unit lengths from a continuous wire supply, mechanism for partially forming said unit lengths, means for engaging said partly formed unit lengths, one at a time, with the end of a finished fabric length, a support for carrying a finished fabric length, means for completing the partly formed fabric units, one at a time, after its engagement with said fabric whereby said unit is secured in said fabric, and means for effecting relative movement of the fabric support and said severing and forming mechanisms whereby a continuous length of fabric is produced.

23. In a machine for forming a continuous length of wire fabric composed of transverse, interconnected, adjacent rows of identical, adjacent, connected wire fabric units, each of said units having an eye part and a hook part mating with the eye part of a unit in an adjacent row, said eye and hook parts connecting together adjacent fabric units in said fabric, the combination of mechanism for severing unit lengths from a continuous wire supply, mechanism for partially forming said unit lengths, means for engaging said partly formed unit lengths, one at a time, with the end of a finished fabric length, a support for carrying a finished fabric length, means for completing the partly formed fabric units, one at a time, after its engagement with said fabric whereby said unit is secured in said fabric, means for effecting relative step-by-step movements of the fabric support and said forming and engaging mechanisms, and means for effecting automatic reversals of said step-by-step movements after a pre-

determined number of steps, whereby a flat web of fabric of predetermined width is produced.

24. In a machine for making a continuous length of wire fabric composed of transverse, interconnected, adjacent rows of identical, adjacent wire fabric units, each of said units having an eye part and a hook part mating with the eye of an adjacent unit in an adjacent row, said mating parts connecting together adjacent units of the fabric, the combination of mechanism for partly forming said fabric units, one at a time, whereby said hook is incompletely formed, a support for carrying the finished length of fabric, means for engaging the partly formed fabric units, one at a time, with the end of the finished fabric carried by said support, means for completing the formation of the hook of the unit after its engagement with said support whereby each of said units, one at a time, is securely connected in said fabric, and means for effecting relative movement of the fabric support and said initial forming mechanism.

25. In a machine for making a continuous length of wire fabric composed of transverse, interconnected adjacent rows of identical adjacent wire fabric units, each of said units having an eye part and a hook part mating with the eye part of an adjacent unit in an adjacent row, said mating parts connecting together adjacent units of the fabric, the combination of mechanism for partly forming said fabric units, one at a time, whereby said hook is incompletely formed, a support for carrying the finished length of fabric, means for engaging the partly formed fabric units, one at a time, with the end of the finished fabric carried by said support, means for completing the formation of the hook of the unit after its engagement with said support whereby each of said units, one at a time, is securely connected in said fabric, means for effecting relative step-by-step movements of the fabric-support and said initial

forming mechanism, and means for effecting an automatic reversal of said step-by-step movements after a predetermined number of steps, whereby a flat web of fabric of predetermined width is produced. 50

26. In a machine for forming a continuous length of flat wire fabric composed of transverse, interconnected, adjacent rows of predetermined length made up of identical adjacent connected wire fabric units, each of said units having an eye at one side of the row in which it is situated and a mating hook at the opposite side of said row, said mating hooks and eyes connecting together the adjacent transverse rows of the fabric and the adjacent units of the rows, the combination of mechanism for severing unit lengths from a continuous wire supply, mechanism for partly forming said fabric unit lengths, one at a time, whereby the hook part is incompletely formed, a reel for carrying a previously completed fabric length, the axis of said reel being located substantially parallel with the transverse rows, means for engaging the partly formed hooks of the incomplete fabric units with the end of the finished fabric carried by 75 said support, means for completing the formation of each of the units, one at a time, after its engagement with said fabric whereby said hooks are completely closed and the units are securely connected to said 80 finished fabric length, means for effecting relative step-by-step axial movements of the fabric reel and said severing, forming, and engaging mechanisms, and means for effecting automatic reversals of said step-by-step movements after a predetermined 85 number of steps in each of two directions, whereby a flat web of fabric of predetermined width is produced.

In witness whereof, I hereunto subscribe my name this 16th day of March A. D., 1914.

CLARENCE H. FREDERICK.
